ATTORNEY.

UNITED STATES PATENT OFFICE

MAURICE M. BALSAM, OF NEW YORK, N. Y.

PRESS FOR MAKING JAWS FOR HAND BAGS

Application filed October 2, 1931. Serial No. 566,573.

This invention relates to presses for making jaws for handbags.

In the manufacture of hand bags comprising a leather or fabric body having free edges at its opening, it has been the common practice to apply to the free edges a pair of jaws pivoted together and formed of a body of metal turned upon itself to leave a channel into which the free edges of leather or fabric are inserted and the side walls of the jaw forced together to grip the edges of the fabric or leather. This necessarily left the metallic jaws exposed. It is now proposed to use jaws made of a channel of a metallic formation with the flanges thereof turned outward from the bag, so that the edges of the leather or fabric may be inserted therein and gripped so that the metal of the jaws is covered instead of leaving the metal exposed.

The object of the invention is to provide a press adapted to be used to clamp the side walls of the channel frame of such an article where the leather or fabric has been inserted and turned back over one of the flanges of such a channel frame.

The invention consists of the construction, combination and arrangement of parts, as herein described, illustrated and claimed:

30 In the accompanying drawing, forming part hereof, is illustrated a form of embodiment of the invention, and a slight modification as to the shape of the dies, in which drawing similar reference characters designate corresponding parts; and, in which:

Figure 1 is a side elevation;

Figure 2 is a fragmentary detail in vertical section, taken longitudinally of the supporting casing of the device;

40 Figure 3 is a fragmentary detail in front elevation showing the relation of the dies; and,

Figure 4 is a fragmentary detail in horizontal section, partly broken away, showing 45 a variation of form of the die and its appli-

cation to a purse or hand bag, the flanges of whose jaws are turned outward.

Referring to the drawing 5 designates a supporting element and at a point below and removed therefrom is disposed a floor or platform 6.

Secured on the supporting element 5 is a casing 7 formed in any suitable way to leave a chamber 8. Disposed in the chamber 8 and arranged for vertical reciprocation is a lever 55 9, the forward end of which is rockably disposed on a pivot 10, which pivot may extend transversely through the wall of the casing 7 adjacent its front end. A toggle 11, by means of a pivot 12 has its lower end secured to the lower end of a vertical, slideable die carrier 13, which is maintained against the front end of the casing 7 for vertical reciprocation by means of a guide plate 14, secured to the casing 7 by means of bolts 15. 65 The upper end of the toggle 11 is pivotally secured to the lever 9 by the pivot 12a.

Secured to the lower end of the die carrier 13 is a male die 16 which may be made of any suitable shape adapted to operate for the 70 purpose disclosed and which may be removably secured by means of a bolt 17.

The casing 7 at its forward end is provided with a downwardly projecting portion 18 formed with a projecting shoulder 75 18a in its forward face, adapted to receive a corresponding shoulder 19a formed on the rear wall of a removable female die 19, which may be secured by a bolt 20 and which is made of suitable contour to adapt it for use 80 for the purposes described.

The female die 19 has formed on its forward face a lip 21 having an inclined upper face arranged in the path of movement of the male die 16 and is provided with a channel 22 arranged between its forward face and the rear portion of the inclined projecting lip 21. The object of the projecting lip 21 is to provide a means for reaching over and under the jaw 28 of the bag frame, the in- 85 90

clined upper surface of the lip 21 forming an anvil against which the male die may press together the free, outwardly projecting edges of the jaw 28 and the channel 22 will receive the bent metal portion of the jaw 28 and its contained fabric or leather edge of the purse or bag 27 without breaking or wrinkling the material.

In Figure 4 is illustrated the form of dies used in round-cornered constructions, and with the exception of the contour thereof is the same as the dies previously disclosed.

Heretofore it has been the usual practice in the art to use hand labor utilizing a mallet and anvil for closing the flanges of the jaws of pocket-books, and one of the objects of this invention is to provide a foot-operated assembly for this purpose. A connecting rod 23 is connected to a foot pedal 24 on the floor or platform 6 and has its upper end connected to the lever 9. The foot pedal 24 is maintained in elevated position and the die 16 in raised position by means of a tension rod 25 having its lower end secured to the foot pedal 24 and its upper end connected to a coil spring 26 the projecting upper end of the latter of which may be inserted into the inclined slot 26a of a bracket 26b secured to the under side of the supporting element 5.

In the operation of the invention the pocket-book 27 is formed so as to leave an opening on one side to include two free edges. The jaw 28 is formed of its component parts and hinged together at their ends to leave the flanges of the channel iron projecting outwardly. The jaws are then inserted over the lip 21 of the female die 19 and the foot pedal 24 operated to force the male die 16 downward crimping the free edges of the jaw 28 against the inclined face of the lip 21. The excess material at the free edge is forced into the channel 22 without breaking or distorting the bent portion of the metallic jaw 28 and without cracking the leather or fabric, which is firmly held to the edges of the flanges of the jaw 28. As best shown in Figure 2 this leaves the upper edge of the purse or pocket-book on its outside completely covered with the fabric or leather material and does not leave any of the metal exposed when the bag is closed.

Having thus fully described the invention, what is claimed as new and desired to be secured by Letters Patent is:

1. A press comprising a hollow head provided with a downward extension, an actuating lever pivoted in the head, a male die slidably supported by the head and connected with the lever, means for rocking the lever, and a female die carried by the extension and disposed in the path of movement of the male die and provided with an inclined face and a channel adjacent thereto.

2. A press comprising a hollow head, an actuating lever disposed in the head, a foot

pedal and connection to the lever, a male die slidably disposed on the head and connected with the lever, and a female die removably secured on the head and provided with a projecting lip having an inclined upper face disposed in the path of movement of the male die and also provided with a channel adjacent said face.

In testimony whereof he has affixed his signature.

MAURICE M. BALSAM.
